UNITED STATES PATENT OFFICE.

HARRY BRIDGMAN SMITH, OF BROOKLYN, NEW YORK, ASSIGNOR, BY MESNE ASSIGNMENTS, TO HOAGUE-SPRAGUE CORPORATION, OF LYNN, MASSACHUSETTS, A CORPORATION OF MASSACHUSETTS.

METHOD OF PRODUCING BOXES AND BOX BLANKS.

Application filed January 12, 1923, Serial No. 612,171. Renewed June 25, 1926.

This invention relates to methods of producing boxes and box blanks which are in general conformity with certain of my previous inventions in this art as disclosed in 5 various patents and pending applications, with important modifications and improvements.

The general object of the invention is to provide "continuous" methods of producing 10 printed, decorated or other boxes and box blanks, said methods being in general agreement with my previous continuous box production methods as disclosed in the above mentioned patents and applications and 15 companion applications executed on even date herewith, with the addition to or incorporation in the continuous method steps of suitable operations which provide desired printed subject-matter on the boxes in ad- 20 vantageous ways.

Another object is to provide an improved 25 method of producing composite box blanks in which free strips or margins of cover paper project beyond certain of the shell edges, to provide for covering and concealing 30 said edges in the completed box, as more particularly explained hereafter.

A great many boxes are furnished with 35 plain or unprinted exterior surfaces and any suitable printed labels may of course be pasted on any or all of the outer faces of such a box by the manufacturer, or by the consumer according to his requirements; but when a large number of boxes are required, 40 of identical form and size and with identical printed matter, the cost of such labeling operations is excessive or prohibitive. Otherwise, in the manufacture of the boxes, printed cover blanks may be supplied and applied 45 to the box bodies or shells, and I have invented box structures, methods of manufacture, and machines for manufacturing boxes automatically and economically in accordance with this plan which may be identified as an individual blank assembly 50 method. In the art previous to my invention just referred to, so far as I am aware, no completely automatic machinery has been available for the production of such covered boxes. Further by the use of my invention or by previous methods, this plan of box production, while satisfactory for many

purposes, does not provide for the great output volume which is provided by my continuous methods above referred to. Of course boxes produced by any of my previous methods, including the continuous methods, may have separate printed labels pasted on, or printing mechanisms may be used to print directly on the covered surfaces of the completed box parts; but all such expedients are unduly troublesome and costly and manifestly undesirable for long-run production where many thousands of boxes of identical character and with identical printed matter are to be produced as economically as possible.

To avoid the above mentioned and other difficulties heretofore existing in the production of printed boxes, my invention comprises, as broadly described, the advancing of a continuous strip or web of box forming material, such as a suitable "cardboard" or chip board, to form the box body or shell, and in suitable way, or at suitable times in relation to the movement of the continuous web, advancing and adhesively securing to a face of the web successive individual cover blanks each of which is printed with the desired indicia for a completed box. While the edges of the cover blanks may be more or less spaced apart, or may overlap more or less, in some cases, without destroying the value of the method, it is usually preferred to feed and affix the cover blanks so that the forward edge of each is located close alongside the rearward edge of the preceding one. The cover blanks may be proportioned so that their side edges are closely in line with the longitudinal edges of the continuous web, that is to say, so that the cover margins do not project; or otherwise, and more desirably in some cases, side marginal portions of the cover blanks project beyond the longitudinal edges of the web and during the advance of the continuous web these margins are turned over and adhesively secured to under marginal surfaces of the shell web. Sections of regular length are then cut from the continuous assembly as above produced, forming individual box blanks, severing operations being performed to separate independently foldable parts of the blanks, as the corner laps and end wings,

either before or after the individual blanks are severed from the continuous assembly. The individual blanks are then folded and secured in box form whereupon the printed matter of the cover blanks appears in the desired and predetermined location on outer surfaces of the completed box part.

In the foregoing general description reference is made to printed sheets or labels and for many purposes such sheets or labels bearing indicia or designs of a practical commercial, or more or less decorative character, are entirely suitable. In a broader aspect of the invention, however, the applied sheets or labels may be treated in other ways to produce the desired effect. For instance, these sheets or labels may be embossed, with or without additional printing, or the individual sheets or labels may even have originally-separate labels or pasters applied to them. Therefore reference will be made hereafter, in some places, and especially in the claims, to imprinted, "treated" or decorated sheets or labels to signify the broader characteristics of such elements, as above sufficiently explained.

Other important features which may be included in connection with those above described are the treatment of the continuous web or shell blank to provide longitudinal folding lines, and in some cases this shell web treatment may be performed before assembly contact of the cover blanks and in other cases afterward, in general conformity with other of my inventions involving continuous production methods, particularly as referred to in the above mentioned companion applications; also, the continuous shell web or the continuous assembly including the cover blanks, may be treated to provide transverse fold lines or creases.

An important variation in the method as above described consists in forming a continuous composite web or blank assembly, including a shell web and a cover web, with or without overturned cover margins, in general accordance with other of my continuous box production methods, and advancing and adhesively affixing successive printed labels to the cover strip or web, this usually being done after the cover web advances toward the point of application to the shell web; although in a broader aspect of the invention the application of the separate printed labels over the cover paper may be performed after assembly contact of the cover web with the shell. Considerable variation is possible in the nature or shape of these labels and the manner in which they are applied, that is to say, with regard to their spacing, or their location on the completed box part.

The characteristics and advantages of the invention are further sufficiently explained in connection with the following detail de-

scription of the accompanying drawings, which show certain exemplifying embodiments of the invention. After considering these, persons skilled in the art will understand that many variations may be made within the principles of the invention; and I contemplate the employment of any methods which are properly within the scope of the appended claims.

Figure 1 is a perspective view sufficiently illustrating one performance of the process up to the point of individual blank cut-off.

Figure 2 is a perspective view of a completed individual box blank.

Figure 3 sufficiently explains intermediate steps or stages of shaping the blank into box form.

Figure 4 is a perspective view of the completed box part.

Figure 5 shows the same box part in reversed position.

Figure 6 is a perspective view sufficiently illustrating one variation of the method.

Figure 7 is a side elevation of the materials and mechanisms shown toward the right in Figure 6.

Figure 8 is a perspective view of a completed box blank produced in the general manner illustrated in Figure 6 but with a variation in the location of the label.

Figure 9 is a perspective view of a completed box bearing labels in two locations, as provided by the arrangement of Figure 6 and the variation indicated in Figure 8.

In the process as illustrated in Figure 1 a continuous web of box body or shell material 1 is advanced from a roll 2 and at a suitable point longitudinal fold lines 3 are produced by suitable means, such as "routers" 4. Narrow longitudinal strips are shortly thereafter removed from the shell web, producing slots 5, which are usually directly in line with the longitudinal fold lines and of the same width, and of a suitable length for the desired end formation of the completed box blank as made clear hereafter. Glue is then supplied to one face of the continuous shell web by a glue roll 6, this being a representative way, which is preferred in many cases, for supplying adhesive to secure the cover blanks.

The cover blanks C are desirably arranged in a stack 8 at a convenient point adjacent to the advancing shell web. The blanks are provided on one face with suitable printed matter which may be of almost any character and occupy substantially any portion of the blank. In the present instance this printed matter is in the form of spaces or panels 9, 10 and 11 corresponding substantially to the central or body section, side walls and end walls of the completed box part. While the blank may in some cases be of more or less irregular or non-rectangular outline, it is usually more convenient and de-

sirable to provide the blanks in rectangular form as shown. They are more desirably arranged with the printed faces upward to avoid any necessity for inverting the blanks prior to application to the shell web.

The individual blanks may be separated from the stack and advanced and applied to the shell web in any convenient or suitable way. In the present example mechanism for this purpose is indicated in a diagrammatic or rudimentary way, this mechanism consisting of a stack-support or holder 12 arranged to reciprocate as shown by the arrows. The forward portion of the stack projects beyond the carrier and co-operates with a selector or feed roll 13. The stack is reciprocated at suitable intervals in relation to the shell-web movement. For instance, just as the rearward edge of one cover blank C is leaving the neighborhood of guide roll 14 over which the shell web passes adjacent to the cover feed mechanism, the stack is moved forward by its carrier and provision may be made at the same time for slightly lowering the leading end of the stack to bring the forward edge of the lowermost cover blank therein in contact with the adhesive surface of the shell web. The advance of the stack continues for a brief space along with the shell web and in this movement the forward edge of the blank, adhering to the shell web, is carried between the selector or feed roll 13 and the shell surface supported on roll 14, and the actions are timed so that the edges of the blanks are brought quite close together as clearly shown in Figure 1, where transverse lines 15 indicate the closely located or contacting edges of adjacent cover blanks on the continuous shell web. Shortly after the cover blank is securely gripped and advanced by the feed roll 13, the stack may be withdrawn by retraction of the carrier 12, and in this movement the just-mentioned cover blank is fully withdrawn from the bottom of the stack, and as the blank proceeds forward under the feed roll it is pressed completely in engagement with the shell web, and the actions are then repeated indefinitely to produce a continuous covered shell web or assembly.

No attempt is made to describe in full the details of the feed mechanism. Any suitable feed mechanism may be employed or any suitable parts may be added to the mechanism diagrammatically illustrated to produce the desired results, and of course with respect to all of the mechanisms above and hereinafter described, it is to be understood that while an important feature of the invention is the adaptation of the methods to performance by machines and preferably by entirely automatic machines, for the sake of high speed and economical pro-

duction, the methods in all their variations are equally well adapted to be performed by hand operations or by the aid of tools of elementary simplicity.

In this particular example of the method the cover blanks have projecting lateral margins 17. To provide for the application of these margins to under marginal surfaces of the shell web after the cover margins are turned over in the manner just below described, a desirable variation in the method is, in some cases, the application of adhesive to the cover blanks instead of to the shell web, and in that case the cover blanks would be glued all over, including the margins, and no precautions would have to be taken to supply additional adhesive for the adaptation of these cover margins to the shell web.

For other reasons, however, it is more desirable in many cases to apply adhesive to the shell web as above described. Therefore when the cover blanks have projecting margins, adhesive may be supplied to these margins or it may be supplied to under marginal surfaces of the shell web as by glue rolls 18. The cover margins 17 are thereafter turned down and under and pressed against the glue stripes on the shell web margins by any suitable mechanisms.

At a suitable point in the advance of the materials, which may in some cases be prior to the application of the cover blanks to the shell web, but more desirably is in some cases, as here shown, after the cover blanks are applied and their margins turned and secured, transverse fold lines 19 are produced by suitable instrumentalities, these fold lines desirably taking the form of deep grooved or "bead" creases.

Mechanisms or operations for producing the transverse fold lines and also for producing slots 5 in the shell web previously referred to are of course located or "timed" so that these parts or elements operate in proper relation to the individual blank elements composing the continuous web or assembly, which are approximately or exactly indicated by the lines 15. For example, slots 5 are produced in the shell web in such positions that after application of the cover blanks the lines 15 defining end limits of the adjacent blanks are at the longitudinal centers of the slots, and similarly the transverse fold lines 19 are produced in equally spaced relation to the blank division lines 15, and usually the fold lines are in a line with the ends of two opposite slots 5.

At a suitable point in the further advance of the materials slits 20 are made in the cover material by suitable devices such as slitting wheels 21, these slits being over the shell slots 5 and being desirably arranged so that a margin 21a of the cover paper projects alongside a longitudinal

edge 22 of the shell, this being an edge of the shell end wing in the completed individual blank, Figure 2.

At a suitable point in the further advance 5 of the materials, say at a relatively fixed point 23, portions are severed from the continuous assembly at regular intervals, the severing cuts being made at such a location or at such a time that the cutting instrumentality is exactly or approximately in line 10 with the blank division lines 15 defining the proper points of separation of the individual blanks. A series of individual blanks B, Figures 1 and 2, is thus produced, each of 15 which comprises a central or body portion a, side wings b, corner laps c projecting from the ends of the side wings, and end wings d, each of these blank portions comprising shell 20 and cover material adhesively applied thereto. The blanks are then folded into box form in one or more intermediate stages or series of operations, these intermediate operations being sufficiently indicated in Figure 3, and comprising turning up the 25 side wings, turning in the corner laps and then turning up the end wings and securing them to outer faces of the corner laps. At any suitable point or stage of operations adhesive may be supplied to parts of the end 30 structure. For instance, before the individual blanks are severed or afterward, at a convenient point, adhesive may be applied to inner faces of the end wings and at the same time or by a different operation adhesive 35 may be also applied to the narrow cover margins 21^a. When therefore the cover wings are turned up and pressed properly against the corner laps they are adhesively secured and retained in position and at or 40 about the same time the narrow cover margins 21^a are pressed and secured against outer faces of the cover paper on the corner laps c adjacent to the vertical corners of the box, as clearly shown in Figure 4, these 45 pressed and adhesively secured cover margins adequately protecting and concealing the side edges of the shell wings d.

A series of complete box parts as shown 50 in Figure 4 is thus produced in very rapid and economical fashion, each of which bears in proper places on its exterior surface the printed subject-matter carried by the originally-separate cover blanks.

The method is susceptible of a great many 55 variations along practically any or all of the lines suggested in my prior applications disclosing continuous production methods of this general class, and especially my companion applications of even date, either for 60 the purpose of improving, simplifying or cheapening the method per se, or for the purpose of producing boxes of other forms. Reference is therefore made to said applications 65 for a full understanding of variations in the methods and box structures, and it

will not be attempted to explain all of these variations herein; but a proper latitude of variation in the structures and methods of the present application will be indicated in the broader claims appended.

Figure 6 illustrates one important variation in the method, in which the shell web 1 is advanced and treated substantially as in the previous instance up to the point of assembly contact, except that the punching of 70 shell slots 5 is omitted in this instance. Instead of applying printed cover blanks directly to the shell web, a continuous web of suitable cover paper 30 is advanced from a roll 31 and the under or inward surface of 75 the cover web is adhesively conditioned by a glue roll 32. The cover web passes on and at a suitable point is brought in adhesive contact with the shell web, and individual printed blanks or labels L may be affixed to 80 the cover web at any convenient or suitable point in its advance. Desirably, however, as in the present example, these labels L are affixed to the cover web before its application to the shell web. For this purpose the 85 labels L are arranged in a stack 33 adjacent to a guide roll 34 over which the cover web passes and adjacent also to a feed roll 35, and the stack is supported by a reciprocating 90 stack carrier 36, the stack carrier and other 95 details of the label feed mechanism being similar to the feed mechanism previously described in connection with Figure 1. The labels in this instance are intended to be located on the central or body section of the 100 completed box, and they are placed in the stack with the printed surfaces upward. The movement of the stack carrier 36 is timed so that the labels are advanced into 105 contact with the cover web and located thereon at the proper points with due regard to the division of the continuous web or blank assembly into individual blanks at a subsequent stage of the process.

Adhesive may be supplied in any convenient or suitable way for securing the labels in position. Desirably, adhesive for this purpose is supplied to the continuous cover web by a glue roll 40, Figures 6 and 7, having a part-cylindrical gluing surface 41 commensurate with the area of the labels. This glue roll is located or timed so that "spots" of glue are applied to the continuous cover web over substantially the exact areas which will be occupied by the labels L, and at the proper point the labels are then advanced and separated from stack 33, applied to and pressed on the glued areas, and they then proceed along with the cover web, which is brought into contact with the advancing 115 shell web 1 and pressed in adhesive contact therewith, for example, by the pressing roll 45.

When the cover web has projecting lateral margins 47, these margins are then turned 120

down and under and pressed on under margins of the shell, and at a suitable point transverse fold lines 50 are produced in the continuous assembly, and narrow strips of the material are punched out, producing slots 51 which are usually in line with and of the same width as the longitudinal fold lines or channels 3, and the continuous assembly is then cut off as at 53, producing individual box forming blanks or blank assemblies B¹, which are substantially the same as the blank assemblies B previously described except that the corner laps and end wings are separated by slots produced by excising portions of the combined materials, and in this example without provision for any cover margins alongside the longitudinal edges of the end wing as in the previous instance, and of course with the important difference that the shell material of the blank is entirely covered exteriorly and along the longitudinal edges by the sheet of cover paper, and the desired printing is supplied in the form of a printed label L affixed to a suitable portion of the exterior cover paper surface, in the present case to the cover body portion a.

Figure 8 shows a smaller printed label L¹ applied to one of the end wing sections of the blank. It is evident that the process may be varied or rearranged to provide for the application of labels in this position, and in fact, when necessary or desirable two or more labels may be applied to a single individual box blank by providing two or more label feed arrangements, parallel or in series, with suitable means for providing adhesive to insure the adhesion of each label in the proper position.

Figure 9 shows, for example, two labels L and L¹ affixed to the outer surface of the completed box in desirable positions.

The completed individual blank of Figure 6 or Figure 8 is then folded into box form in a manner which is sufficiently obvious from the previous explanation, adhesive being properly supplied as previously explained, to secure the end wings to the outer surfaces of the corner laps.

Words used herein to indicate relative location, that is, such words as top and bottom, upper and lower, and similar words, are generally used only in a relative sense, since evidently the relative locations of parts may in many cases be changed and, for instance, the positional relation of the principal materials in the performance of the process may be in many cases reversed. It is to be understood also that the showing in the drawings is largely dictated by illustrative convenience and the general course of materials and the arrangement of parts in a complete machine or process lay-out may be quite different from the diagrammatic indications in the drawing.

I claim:

1. A method of producing printed box blanks, comprising advancing a continuous web of shell material, adhesively conditioning a surface thereof, advancing successively individual printed sheets, securing the successive sheets to the adhesive surface of the web, and severing the web assembly at regular intervals to produce individual printed blanks. 70

2. A method of producing printed box blanks, comprising advancing a continuous web of shell material, adhesively conditioning a surface thereof, advancing successively individual printed sheets, securing the successive sheets to the adhesive surface of the web, turning and affixing projecting margins of the printed sheets to under marginal surfaces of the shell web, and severing the web assembly at regular intervals to produce individual printed blanks. 80

3. A method of producing printed box blanks, comprising advancing a continuous web of shell material, adhesively conditioning a surface thereof, advancing successively individual printed sheets, securing the successive sheets to the adhesive surface of the web to form a substantially continuous cover layer thereon, and severing the web assembly at regular intervals corresponding substantially to the printed sheet ends to produce individual printed blanks. 90

4. A method of producing printed box blanks, comprising advancing a continuous web of shell material, adhesively conditioning the surface thereof, advancing successively individual printed sheets, securing the successive sheets to the adhesive surface of the web to form a substantially continuous cover layer thereon, turning and affixing projecting margins of the printed sheet to under marginal surfaces of the shell web, and severing the web assembly at regular intervals corresponding substantially to the printed sheet ends to produce individual printed blanks. 100

5. A method of producing box blanks, comprising advancing a continuous web of shell material, cutting the web to produce individual blank formations thereon, advancing printed sheets in regular order and securing them adhesively upon the shell web in locations corresponding to individual blanks to be produced, and severing the continuous assembly so formed at regular intervals to produce individual blanks. 115

6. A method of producing box blanks comprising advancing a continuous web of shell material, cutting the web to produce individual blank formations thereon, applying adhesive to the shell web, advancing printed sheets in regular order and securing them adhesively upon the shell web in locations corresponding to individual blanks to be produced, and severing the continuous as- 120
125
130

- sembly so formed at regular intervals to produce individual blanks.
7. A method of producing box blanks, comprising advancing a continuous web of box-board, forming longitudinal folding channels on one face thereof, coating one surface of the web with adhesive, feeding successive printed blanks and applying them to the adhesive web surface in regular order and with the successive blanks substantially in contact with each other, and serving the assembly transversely at regular intervals corresponding to the blank ends to produce individual box blanks.
8. A method of producing box blanks, comprising advancing a continuous web of box-board, forming longitudinal folding channels on one face thereof, coating one surface of the web with adhesive, feeding successive printed blanks and applying them to the adhesive web surface in regular order and with the successive blanks substantially in contact with each other, and with margins of the blanks projecting beyond longitudinal edges of the web, turning and securing the projecting margins to marginal faces of the web, severing the assembly transversely at regular intervals corresponding to the blank ends to produce individual box blanks.
9. A method of producing printed boxes, comprising advancing a continuous web of shell material, adhesively conditioning a surface thereof, advancing successively individual printed sheets, securing the successive sheets to the adhesive surface of the web, severing the web assembly at regular intervals to produce individual printed blanks, and folding and securing the individual blanks in box form.
10. A method of producing printed boxes, comprising advancing a continuous web of shell material, adhesively conditioning a surface thereof, advancing successively individual printed sheets, securing the successive sheets to the adhesive surface of the web to form a substantially continuous cover layer thereon, severing the web assembly at regular intervals corresponding substantially to ends of the printed sheets to produce individual printed blanks, and folding and securing the individual blanks in box form.
11. A method of producing boxes, comprising advancing a continuous web of box-board, forming longitudinal folding channels on one face thereof, coating one surface of the web with adhesive, feeding successive printed blanks and applying them to the adhesive web surface in regular order and with the successive blanks substantially in contact with each other, severing the assembly transversely at regular intervals corresponding to the ends of the blanks to produce individual box blanks, and folding and securing the individual blanks in box form.
12. A method of producing boxes, comprising advancing a continuous web of box-board, forming longitudinal folding channels on one face thereof, coating one surface of the web with adhesive, feeding successive printed blanks and applying them to the adhesive web surface in regular order and with the successive blanks substantially in contact with each other, and with margins of the blanks projecting beyond longitudinal edges of the web, turning and securing the projecting margins to marginal faces of the web, severing the assembly transversely at regular intervals corresponding to the ends of the blanks to produce individual box blanks, and folding and securing the individual blanks in box form.
13. A method of producing printed box blanks, comprising advancing a continuous web of box material, advancing successively individual printed sheets, securing the successive sheets to a surface of the web, and severing the web at regular intervals to produce individual printed blanks.
14. A method of producing printed box blanks, comprising advancing a continuous web of box material, advancing successively individual printed sheets, securing the successive sheets to the web to form a substantially continuous layer thereon, and severing the web assembly at regular intervals corresponding substantially to the printed sheet ends to produce individual printed blanks.
15. A method of producing printed box blanks, comprising advancing a continuous web of box material, adhesively conditioning a surface thereof, advancing successively individual printed sheets, securing the successive sheets to the adhesive web surface, and severing the web assembly transversely to produce the individual printed blanks.
16. A method of producing printed box blanks, comprising advancing a continuous web of box material, advancing successively individual printed sheets, supplying adhesive to secure the successive sheets to a surface of the web to form a substantially continuous layer thereon, and severing the web assembly transversely at intervals corresponding substantially to the printed sheet ends to produce individual printed blanks.
17. A method of producing printed box blanks, comprising advancing a continuous web of box material, advancing printed sheets in regular order and securing them upon a surface of the web in locations corresponding to individual blanks to be produced, and severing the continuous assembly so formed at regular intervals to produce individual blanks.
18. A method of producing box blanks, comprising advancing a continuous web of body material, producing longitudinal slots therein, applying successive individual

5 sheets of cover material to a face of the web and overlying the slots, slitting the cover material overlying the slots on lines spaced from certain of the slot edges, and severing the composite web transversely to produce individual blanks.

- 10 19. A method of producing box blanks, comprising advancing a continuous web of shell material, producing parallel slots in the web at blank intervals, the slots being spaced inward from the shell edges, applying successive individual sheets of cover material and securing them to a face of the web with portions of said sheets overlying the slots, slitting the cover material on lines spaced away from certain of the slot edges, and severing the composite web transversely on lines intersecting the slots to produce individual blanks.
- 15 20. A method of producing box blanks, comprising advancing a continuous web of shell material, producing parallel slots in the web at blank intervals, the slots being spaced inward from the shell edges, applying successive individual sheets of cover material and securing them to a face of the

20 web to form a substantially continuous cover layer with portions of said sheets overlying the slots, slitting the cover material on lines spaced away from certain of the slot edges, 30 and severing the composite web transversely on lines intersecting the slots to produce individual blanks.

25 21. A method of producing box blanks, comprising advancing a continuous web of shell material, slotting the shell at blank intervals, advancing and securing successive individual cover sheets to a face of the shell web, the cover sheets being dimensioned to have longitudinal margins projecting beyond the longitudinal shell edges, folding and securing the projecting sheet margins to the opposite marginal faces of the shell, slitting said sheets on lines spaced from certain of the slot edges, and severing the web 40 assembly on transverse lines intersecting the slots to produce the individual blanks.

Signed at New York city, in the county of New York and State of New York this 20th day of December, A. D. 1922.

HARRY BRIDGMAN SMITH.
